UNITED STATES PATENT OFFICE.

JOHN G. LOW, OF CHELSEA, MASSACHUSETTS.

SODA-FOUNTAIN.

SPECIFICATION forming part of Letters Patent No. 408,888, dated August 13, 1889.

Application filed August 29, 1888. Serial No. 284,054. (No model.)

To all whom it may concern:

Be it known that I, JOHN G. LOW, of Chelsea, in the county of Suffolk and State of Massachusetts, have invented a new and useful Improvement in Soda-Fountains, whereof the following, reference being had to the accompanying drawings, is a specification in such full and complete and accurate terms as to allow others skilled in the art to make and use the invention.

It is considered desirable to have soda-fountains present an ornamental and artistic appearance, and it is also thought necessary that they should be provided with an ice-box in which are contained the sirup-tanks and certain coils of pipe and reservoirs, through which the aerated waters pass on their way through the fountain to the draft-tubes, being cooled in their passage. It is also considered desirable that the ornamental exterior of the fountain should be so independent of the inclosed ice-box that it shall not chill and collect moisture from the air upon its exterior surface. No form of decoration of the soda-fountain has yet been found superior to polished marble; but this material is exceedingly expensive.

Baked clay, which can be readily modeled in shape and glazed with any desirable color, presents a material vastly better than marble, both for beauty and ease of working, were it not for the difficulty hitherto experienced of applying it. I have, however, succeeded in devising a form of structure which is well adapted for incrustation with glazed or enameled tile; also, a system of subdivision of the incrustation, so as to present great opportunities for variety with ease of application, which I now explain.

In the drawings, Figure 1 is a front elevation, and Fig. 2 a vertical section through the central draft-tube, of a fountain embodying my invention.

B is the ice-box proper, in the cavity of which is placed, as usual, a metallic or other suitable lining C, and which contains the sirup-cans E and the coolers G G' G² G³. Draft-tubes g are connected with the pipes of these coolers, and sirup tubes and cocks e are connected with the several sirup-cans. There is a cover to this ice-box, which may be of hinged flaps or may be a removable cover fitting the recess.

The parts hitherto described are common to all soda-fountains.

When a soda-fountain is placed next the wall of the building or against a partition, no incrustation is applied on the part which is next the wall; but on the part exposed to the eye of the spectator it is usual to construct the ice-box of polished marble, and in a few instances of cheap portable fountains a wooden ice-box has been used. The casing has been usually separated from the ice-box proper by an air-space.

In my invention I erect on the exposed sides and ends of the fountain a casing A, of stone, wood, or iron, the interior of which casing is proximately parallel to the exterior of the ice-box B, and the exterior of which casing A follows roughly the proposed contour of the tile-incrustation, as shown in Fig. 2. This casing A need not be of very perfect material or finish, and it may be, if desirable, made in several parts, cemented or joined together. This casing A is separated by a space of one or two inches or more from the ice-box B, which space is shown in the drawings as D, and is packed with what is commonly known as "mineral wool," sometimes called "mineral cotton," being furnace-slag in a state of minute subdivision and of cellular or fibrous structure, which is made by blowing steam through a screen of molten slag as it is discharged from the furnace.

The incrusting tiles of this fountain are of four generic sorts—cornice-tiles, belt-tiles, pilaster-tiles, and panel-tiles—and the cornice and belt tiles have two subdivisions—namely, tiles with return modeling and tiles with running modeling. The pilaster-tiles are usually made with returns, and the panel-tiles have only surface modeling, although this may not be the same on any two tiles.

In the drawings, a represent the cornice-tile with the running modeling. They form the center of the upper part of the fountain, and are arranged to cover in the part from the ice-box outward. They are recessed for the reception of the covers F F' of the ice-box. This construction of cornice enables either flap of the ice-box to be raised at will, and also binds together very firmly the incrustation with the casing A. In consequence, however, of this arrangement of cornice-tile, the casing A is necessarily of less height than the wall of the

ice-box B. Below this cornice there is a course of belt-tile $b b'$, in which the parts b are parts with a running modeling, and the parts b' have return modeling. This belt course in 5 the specimen produced forms the frieze of the entablature. Below this again is another course of belt-tile $c c'$, in which the parts c have a running modeling and the parts c' a return modeling. This forms the architrave 10 of the structure. Below this again, at the exterior corners of the structure, are the pilaster-sections d , which are made with return modeling, and between the pilaster-sections are the panel-sections $k k', l l', m m', n n', o o'$, and $p p'$. These panel-sections are modeled to make up some agreeable figure, perhaps alike on each of the several sections, perhaps a composite figure, some portion of which is exhibited on each of the sections, the sections 15 in that case differing entirely each from the other. The number of tile going to make up the panel-section may be greatly varied; but the peculiarity of the tile making up these panel-sections is that they are surface-mod- 20 eled and surface-glazed only, while the tile of the belt courses and the tile of the cornice courses and the tile of the pilasters are return-modeled and return-glazed on some or all of their members. The pilaster and panel 25 members rest on a pedestal which is made up of belt courses.

$i i'$ are the belt course forming the crown of the pedestal, of which the tiles i have running modeling and the tiles i' return model- 30 ing.

$f f'$ is the die or dado of the pedestal, of which the tiles f have a running modeling and the tiles f' a return modeling. The tiles f are perforated with comparatively large holes 40 for the passage of the sirup-tubes e . These holes should be considerably larger than the tubes, because in the irregular shrinking of the tile it will be difficult to make the parts come together correctly unless an allowance 45 is made at this place for all the irregularity which will occur. Below this dado-section is another belt course $q q'$, surface-modeled on the tiles q and return-modeled on the tiles q' , forming the base-molding. Below 50 this, again, is a belt-section formed of the tiles $r r'$, of which the tiles r have a running modeling and the tiles r' a return modeling. These tiles $a a', b b', c c', d, f f', i i', k k', l l', m m', n n', o o', p p', q q'$, and $r r'$ are affixed firmly 55 by cement or cramps to the exterior of the casing A. The layer of cement is marked in Fig. 2 of the drawings h and is of pretty even thickness.

It will be seen readily that a great variety 60 of modeling and a great variety of color with a most brilliant surface texture can be obtained in this way, and that it would be almost impossible to absolutely duplicate any fountain, because of the difficulty of perfect 65 reproduction of the glaze. It will also be seen that out of two or three varieties of cornice, base, pilaster, and panels the variety of model-

ing may be varied and the various fountains given individual character of modeling in a geometrical progression of number—that is, 7c with two sets of cornice, pilasters, panels, and base-tile there could be sixteen fountains of individual appearance set up, and if each belt is considered by itself the number would be greatly increased; also, it can be readily seen 75 that the length of the fountain can be increased or diminished and the number of sirups served varied within reasonable limits at comparatively slight expense by adding single panel and belt sections or panel and 80 pilaster sections, or both, with very little cost or trouble.

As a result of this form of construction, a fountain giving a much greater show and presenting a much finer appearance than the 85 marble fountain now in use for the same service and with substantially the same interior structure can be furnished on remunerative terms to the manufacturer for about three-fourths of the cost of a polished-marble fount- 90 ain.

Having thus described my invention, I claim and desire to secure by Letters Patent—

1. A soda-fountain composed of an ice-box B and an inclosing exterior casing A, separated from said ice-box by the space D, and a tile-facing attached to the exterior of said casing and composed of small tiles formed with closely-abutting edges and of approximately uniform thickness, each of said tiles 100 carrying on its surface a part of a composite intaglio and relief design larger than itself, the lower belt tiles and panels and the ice-box and casing beneath the tile being perforated from front to back with holes for the 105 passage of the draft and sirup tubes $g e$, substantially as and for the purpose described.

2. The combination of the casing A, formed with a plane surface on its interior and an irregular surface roughly conforming to the exterior surface of its incrusting tile, with the incrusting tile and with the cement between the casing A and the tile, and with a cornice $a a'$, which projects outward beyond the exterior surface of the next adjacent tile and inward beyond the inner surface of the casing A, substantially as described.

3. The combination of the ice-box B and inclosing-casing A of said ice-box, the height of which is less than the height of the ice-box, 120 and cornice a , extending outward from the ice-box B over and beyond the top of the casing A, and the incrusting tile surface exterior to said casing A and fastened thereto by cement, and containing panel and belt tile 125 perforated for the passage of the draft and sirup tubes $g e$ through holes in said tile larger than the size of the tube, said tile-surface being modeled and glazed, substantially as and for the purposes described.

JOHN G. LOW.
